MADISON M. LIFF, OF LOS ANGELES, CALIFORNIA.

PUMP.

1,390,453.

Specification of Letters Patent. Patented Sept. 13, 1921.

Application filed March 19, 1920. Serial No. 387,066.

To all whom it may concern:

Be it known that I, MADISON M. LIFF, a citizen of the United States, residing at Los Angeles, in the county of Los Angeles and 5 State of California, have invented new and useful Improvements in Pumps, of which the following is a specification.

This invention relates to a pump mechanism, more particularly designed for oil 10 wells and one of the objects of the invention is to provide means for emptying the pump when the same is to be pulled from the well so as to insure a perfectly dry well.

Another object of the invention is to provide 15 clutch means for easily and quickly attaching or detaching the rod to and from the plunger.

Another object of the invention is to provide means for insuring a practically perfect 20 vacuum above the standing valve including means for providing a supply of reserved packing and lubricant.

This invention also consists in certain other features of construction and in the 25 combination and arrangement of the several parts, to be hereinafter fully described, illustrated in the accompanying drawings and specifically pointed out in the appended claims.

30 In describing my invention in detail, reference will be had to the accompanying drawings wherein like characters denote like or corresponding parts throughout the several views, and in which:—

35 Figure 1 is a sectional view of the invention with parts shown in elevation.

Fig. 2 is an enlarged detail view of the clutch mechanism.

40 Fig. 3 is an enlarged detail view of the packing means.

Fig. 4 is an enlarged detail view of the emptying means.

In these views 1 indicates the pump barrel which is formed of sections, said sections 45 being connected together by the coupling rings 2. 3 indicates the pump rod which has its lower end tapered as at 4 and above this tapered part the rod is formed with the recesses 5. A coupling 6 is connected with 50 the plunger barrel 7 by the yoke 8, said yoke being bowed as shown so that it will offer but little resistance to the flow of fluid from the top of the plunger barrel. The block 6 is provided with the bore 9 at its upper part 55 to receive the lower end of the rod 3, said

bore being shaped to conform to the shape of said rod. Lateral openings 10 pass through the walls of the block and these openings receive the wedge-shaped sliding dogs 11 which have their wedge-shaped ends 60 placed into the recesses 5 in the rod by means of the flat springs 12 connected by the block. As will be seen in this position of the dogs the rod 3 will be locked to the clutch block.

Trip levers 13 are pivotally mounted in 65 the block with their short arms engaging recesses 14 formed in the dogs. The long arms extend outwardly from the sides of the block and are adapted to be engaged by the annular member 15 which is of wedge-shape 70 in cross section and has its neck fitting between the ends of two of the sections of the pump barrel and held in position by one of the coupling rings 2. It will thus be seen that when the outer arms of the trip levers 75 13 strike the wedge-shaped part of the member 15 they will be moved downwardly so that the short arms will force the dogs outwardly against the springs and thus release the pump rod from the clutch block. 80

The plunger barrel 7 is of cylindrical form and carries a valve seat 16 at its lower end, said seat receiving the ball valve 17. The packing for this plunger barrel consists of the upper and lower packing seats 18 which 85 are placed between the ends of adjacent sections of the pump barrel and secured in position by the coupling rings. These seats are provided with the curved walls 19 for forcing the packing 20 against the pump 90 barrel. A cylinder 21 is located around the plunger barrel with its ends spaced from the packing seats and this cylinder is supported by a ring 22 which fits between the ends of two sections of the pump barrel and 95 is held in position by one of the coupling rings. The space between the said cylinder 21 and the pump barrel is partly occupied by the reserved packing and this space also receives the compression springs 23 which 100 have their ends bearing against the said reserved packing and the ring. These springs tend to force the packing against the curved walls of the packing seats and these walls force the packing inwardly against the 105 plunger barrel thus forming a practically air-tight packing for the plunger barrel. The cylinder holds the reserved packing away from the moving plunger barrel so as to protect the same. This reserved packing 110

is supplied with lubricant and thus the reserved supply of lubricant is held in a space between the cylinder and pump barrel.

A sleeve 24 is located below the lower 5 packing seat and forms an extension thereof to receive the lower end of the plunger barrel.

A casting 25 formed with the valve seat 26 is located in the pump barrel adjacent 10 its lower end and this casting is located between the ends of two sections of the pump barrel and is secured in place by one of the coupling rings. The valve seat 26 supports the ball valve 27 and a cage 28 is detachably 15 secured to the casting for guiding the valve 27 to its seat. The upper end of the cage carries a projection 29 which is adapted to strike the ball valve 17 and force the same from its seat when the plunger barrel is released from the pump rod by the coupling 20 means before described.

I also provide means for raising the valve 27 off its seat when said plunger barrel is released from the rod. Such means consists of a plunger 30 having its lower end 25 entering an opening 31 in the casting 25 and its reduced upper end slidably secured to the cage by the bolts 32. A spring 33 in the opening 31 holds the plunger in its upper 30 position. The upper end of the plunger is provided with a head 34 which is adapted to be struck by the descending end of the plunger barrel to force the plunger 30 downwardly. A wedge member 35 is slidably 35 mounted in a lateral opening 36 formed in the cage above the valve seat and the outer end of said member engages a recess 37 formed in the plunger 30. This recess is provided with an inclined wall so that as the 40 plunger is lowered the inclined wall will force the wedge member 35 inwardly so as to raise the valve 27 off its seat. In this way both the valves will be raised off their seats when the plunger barrel is released 45 from the pump rod so that the fluid will drain from said plunger barrel and the space below into the well.

The lower end of the pump rod is provided with the reduced extension 38 which 50 is perforated and filtering means may be placed around said extension, such means consisting of the cups 40 which carry suitable filtering material, the lower end of the extension is closed by the cap 25. As the 55 specific arrangement of these filtering means forms no part of my invention they will not be described in detail.

When the pump rod is reciprocated the upward stroke of the plunger barrel will 60 create a suction in the pump barrel below the plunger and this suction will cause the oil to flow through the filter caps into the extension, and from the extension the oil will flow into the lower end of the pump 65 barrel, raising the valve 27 off its seat and

entering the space above said valve. On the downward stroke the valve 27 will be seated and the oil above the valve will be caused to pass into the plunger barrel, raising the valve 17 off its seat by the pressure created. 70 The oil in the plunger barrel will be forced upwardly by the oil entering the barrel and thus the oil will flow from said plunger barrel through the yoke into the pump barrel and thus be lifted to the outlet of the pump. 75

When the pump is to be lifted the rod 1 is moved upwardly far enough to cause the trip levers 13 to strike the wedge-shaped member 15 to release the dogs from the rod. The plunger barrel will then drop back until its ends strike the head 34 of the plunger 80 30 so as to cause the parts to raise the valves 17 and 27 off their seats and permit the oil to return to the well. The parts remain in this position until the pump rod 85 is again lowered into the clutch block and engaged by the dogs.

The ball valve in the bottom of the plunger removes all tendency of the liquid therein to rush back and fill the vacuum being 90 formed below as the plunger is on its upward stroke. The system of packing around the outside of the plunger completely prevents the return of fluid or air from above, and insures a complete intake 95 from the well through the valve just above the filter. This system of packing is so arranged as to hold in reserve a large surplus of fresh clean packing thoroughly lubricated ready for supplying the worn out portion in contact with the plunger. The reserve packing is not in contact with the plunger until required by the operation of the pump. 100

The filtering means will prevent all objectional matter such as clay, mud, sand and the like from entering the pump to clog and cause wear of the parts of the same. 105

It is thought from the foregoing description that the advantages and novel features 110 of my invention will be readily apparent.

I desire it to be understood that I may make changes in the construction and in the combination and arrangement of the several parts, provided that such changes fall within 115 the scope of the appended claims.

What I claim is:—

1. A pump of the class described comprising a pump barrel, a plunger barrel within the same, a pump rod, clutch means for connecting the same to the plunger barrel, a valve located at the lower end of the plunger barrel, packing means for said plunger barrel, a valve at the lower end of the pump barrel, and means for moving both valves 120 off their seats when the plunger barrel is released from the pump rod by the clutch means.

2. A pump of the class described comprising a pump barrel, a plunger barrel therein, 125

a pump rod, means for detachably connecting the rod with the plunger barrel, a valve seat at the lower end of the plunger barrel, a ball valve for engaging said seat, a valve seat at the lower end of the pump barrel, a ball valve for engaging said seat, a cage carried by the seat at the lower end of the pump barrel, a projection on said cage for engaging the ball valve of the plunger barrel
 5 and means for forcing the lower valve off its seat by the plunger barrel when the same is released from the pump rod.
 10 3. A pump of the class described comprising a pump barrel, a plunger barrel therein, a pump rod, means for detachably connecting the rod with the plunger barrel, a valve seat at the lower end of the plunger barrel, a ball valve for engaging said seat, a valve seat at the lower end of the pump barrel, a ball valve for engaging said seat, a cage carried by the seat at the lower end of the pump barrel, a projection on said cage for engaging the ball valve of the plunger barrel and means for forcing the lower valve off its seat by the plunger barrel when the same is released from the pump rod, and packing means for the plunger barrel.
 15
 20 4. A pump of the class described comprising a pump barrel, a plunger barrel therein, a pump rod, means for detachably connecting the rod with the plunger barrel, a valve seat at the lower end of the plunger barrel, a ball valve for engaging said seat, a valve seat at the lower end of the pump barrel, a ball valve for engaging said seat, a cage carried by the seat at the lower end of the pump barrel, a projection on said cage for engaging the ball valve of the plunger barrel and means for forcing the lower valve off its seat by the plunger barrel when the same is released from the pump rod, said means including a spring pressed plunger having a head adapted to be struck by the plunger barrel and a sliding member carried by the
 25 cage and adapted to be forced inwardly by said spring pressed plunger to force the valve off its seat.
 30

4. A pump of the class described comprising

ing a pump barrel, a plunger barrel therein, a pump rod, means for detachably connecting the rod with the plunger barrel, a valve seat at the lower end of the plunger barrel, a ball valve for engaging said seat, a valve seat at the lower end of the pump barrel, a ball valve for engaging said seat, a cage carried by the seat at the lower end of the pump barrel, a projection on said cage for engaging the ball valve of the plunger barrel and means for forcing the lower valve off its seat by the plunger barrel when the same is released from the pump rod, and packing means for the plunger barrel.
 35
 40 5. A pump of the class described comprising a pump barrel, a plunger barrel therein, a pump rod, means for detachably connecting the rod with the plunger barrel, a valve seat at the lower end of the plunger barrel, a ball valve for engaging said seat, a valve seat at the lower end of the pump barrel, a ball valve for engaging said seat, a cage carried by the seat at the lower end of the pump barrel, a projection on said cage for engaging the ball valve of the plunger barrel, means for forcing the lower valve off its seat by the plunger barrel when the same is released from the pump rod, packing means for the plunger barrel and filtering means at the end of the pump barrel.
